DRIVE FOR INTERMITTENTLY FEEDING A
PREDETERMINED LENGTH OF WEB MA-
TERIALClaude V. Allen, Richmond, Va., assignor to The Intra-
Roto Machine Company, Inc., Richmond, Va., a cor-
poration of VirginiaFiled Mar. 25, 1960, Ser. No. 17,582
3 Claims. (Cl. 93—58.3)

This invention relates to an improved feed-up drive for sheet material and more particularly to a drive system for intermittently feeding a predetermined length of continuous web material, especially for use with a press such as a box, or carton, blank forming machine or similar machine wherein it is necessary to imprint, cut or otherwise treat strip material, for instance paper or cardboard, fed from a reel and wherein the strip or web must be stopped during a given interval for allowing the cutting, printing or other treating operation to proceed.

In known apparatus of this character, intermittent drives are used usually combined with braking or looping means applied to the web. To change the length of web feed for different sized cartons, it is generally necessary to stop the machine and change a gear in the drive, or adjust a crank length or the like. During operation of the known machines, the mass and inertia of the drive mechanism and web are such that it is difficult to stop the drive and web immediately during each feed portion of a cycle. Consequently, small inaccuracies of feed creep into the operation which cumulatively require frequent stoppages of the machine for adjustment of the web feed length, in spite of the complex apparatus provided to make fine adjustments automatically.

It is a primary object of the present invention to provide an improved feed mechanism which avoids the aforementioned difficulties.

It is a further important object of the invention to provide an improved intermittent feed drive which may be adjusted to vary the length of the web fed during each advancing operation, avoiding the need to stop the machine to change the gears or crank, or otherwise adjust the mechanism.

It is another object of the invention to provide an improved feed-up drive for a press which properly proportions the web stoppage time in synchronism with the closing of the press members and provides appropriate acceleration and deceleration intervals on starting and stopping of the web.

Yet another object of the invention is to provide an improved feed-up drive for a cutter-creaser which employs a pair of elliptical gears in cooperation with a planetary gear system to reciprocate a rack for driving the web feed rolls, the rolls being disconnected from the rack by an overrunning clutch during movements of the rack in one direction and being connected by the clutch during movements in the other direction.

A still further object of the invention is to provide an improved feed-up drive, of the character indicated above, in which a normally fixed ring gear of the planetary system is provided with means for turning thereof to vary the length of the rack stroke and thus vary the length of the web feed.

Yet another object of the invention is to provide an improved feed-up drive of the indicated construction wherein manual and/or automatic means are provided for turning said normally fixed ring gear, whereby to provide fine and coarse adjustments to vary the length of the web feed.

The novel features that are considered characteristic of the invention are set forth with particularity in the appended claims. The invention itself, however, both as to

2

its organization and its method of operation, together with additional objects and advantages thereof, will best be understood from the following description of specific embodiments when read in connection with the accompanying drawings, wherein like reference characters indicate like parts throughout the several figures and in which:

FIG. 1 is a diagrammatic elevational view of a blank forming machine comprising an improved feed-up drive in accordance with the present invention;

FIG. 2 is a diagrammatic perspective view of a portion of the feed-up drive;

FIG. 3 is a perspective view similar to that of FIG. 2, but of another portion of the feed-up drive and looking in the opposite direction;

FIG. 4 is an elevational diagram of the planetary gear system employed in the feed-up drive showing an intermediate position of the planetary gear in broken lines;

FIG. 5 is a vertical section of a portion of a preferred embodiment of the feed-up drive showing the planetary gear system and related parts housed in an appropriate casing;

FIG. 6 is a side elevational view partly in section taken on the line 6—6 of FIG. 5, and

FIG. 7 is a side elevational view partly in section taken on the line 7—7 of FIG. 5.

Referring now more particularly to the drawings, specifically to FIG. 1, a press 10 is, for example, diagrammatically illustrated as a blank forming machine of conventional construction in which has been incorporated an improved feed-up drive according to the present invention. As will become apparent hereinafter, this feed-up drive may readily be associated with other types of press apparatus wherein the press members are intermittently closed or operated. The machine embodies upper and lower die cutters 11 and 12 which are relatively reciprocated between open and closed positions by conventional means including one or more eccentrics 13.

The web 15 of paper, cardboard or other suitable strip material is fed between the dies 11, 12 from a press or an unwind roll, under a dancer roll 16, between pull rolls 17 and through two sets of feed rolls 18 and 19. A variable speed power source 20 drives the die cutter eccentrics 13 through pulleys 21 and 22 linked by the timing belt 25 which also is trained under guide pulley 26 and over drive pulley 28 to drive through its shaft 32 a feed-up unit 30 which constitutes the present invention. In this manner, timing belt 25 synchronizes the feed of paper web 15 with the opening and closing of the die cutters 11 and 12.

The construction and operation of the improved feed-up drive 30 will be best understood by reference to the diagrams of FIGS. 2-5. An elliptical gear 34, preferably having a velocity ratio of approximately 2 to 1 for the application described, on shaft 32 meshes with a similar elliptical gear 35 in such manner that when gear 34 rotates approximately 255°, the gear 35 rotates through 180°; and when gear 34 rotates the remaining 105°, the gear 34 again rotates 180°. By this arrangement, after a cut is made and the dies 11 and 12 are opened, the web 15 is advanced by the feed-up drive while the crankshaft turning the die eccentrics 13 is rotated 255°. While the crankshaft is rotated the remaining 105° of a single blank forming cycle and the cutting dies are closed, the elliptical gear 35 rotates its remaining 180° and the web 15 is stopped from advancing and is held stationary.

The gear 35 is fixed on a shaft 36 which drives a planetary gear drive system which is of special design to enable simplicity of construction while enabling maximum adjustment of the feed-up. This system, in lieu of a sun gear, includes a crank 37 on the shaft 36 and which revolves a shaft 38 on which is journaled a planetary gear or pinion 39 in mesh with a main gear in the form of an internal ring gear 40. As will become apparent, the sys-

tem can be designed with a sun gear as the main gear instead of the ring gear or in conjunction therewith, but this would involve greater cost and be more space consuming.

A roller 41 is mounted on a stub shaft 42 projecting from pinion 39, as best seen in FIGS. 3 and 4. The roller 41 operates in the slot of a Scotch yoke 43 affixed at one end of a rack 45, causing the rack to reciprocate as shown by the arrow in FIG. 3. The rack 45 is connected by a suitable gear train, to be hereinafter described, to drive the pairs of feed rolls 18 and 19 for intermittently advancing the web 15 to the dies 11 and 12.

Preferably, the axis of shaft 42 and roller 41 is on the center line or pitch circle of the teeth of planet gear 39 and ring gear 40, and the pitch circle of ring gear 40 is made exactly twice that of planet gear 39. Under these conditions, 180° rotation of planet gear 39, from its position shown in solid lines in FIG. 4 to the position shown in phantom lines, will move the roller 41 and hence rack 45 a maximum distance, equal to the diameter of the pitch circle of gear 40, in a straight line along a diametrical line E—E which is parallel with the length of rack 45. Continuation of rotation of gear 39 for another 180° returns the roller to its initial position. Obviously, the use of a sun gear would complicate the design to obtain the maximum and straight line movement of the roller 41.

In the position illustrated in FIG. 4, the axis of the planet pinion 39 is also on the line E—E when the roller 41 is in its extreme position, that is, in starting position. If, however, the ring gear is first turned so that pinion 39 starts from an initial position in which its center is offset from the line E—E, the roller 41 will still move along the diametrical line E—E but its length of travel will be reduced and the stroke of the rack 45 will thereby be shortened. This affords a desirable way for adjusting the length of travel of rack 45 and hence the feed of web 15, as will be more fully explained hereinafter.

Meshing with the gear teeth of rack 45 is a gear 46 keyed to a drive shaft 47 which is coupled to a main drive gear 50 by an overrunning clutch 48. Thus, referring to FIG. 3, movement of rack 45 toward the right drives gear 50 in the counterclockwise direction. When, however, rack 45 moves toward the left, gear 46 is reversed, but clutch 48 uncouples and gear 50 is not reversed. The set of drive rolls 19 are driven by gear 50 to advance the web 15 by means of spur gear 51 meshing with drive gear 50 and with a spur gear 52. Gear 51 is keyed to the shaft of the lower drive roll 19, while gear 52 is keyed to the shaft of the upper drive roll. A similar set of gears 53 and 54 drive the pair of feed rolls 18. An overrunning, or backstop, clutch 55 couples gear 54 to the shaft of upper feed roll 18 and insures that the web 15 will remain stationary on the return stroke of rack 45 in spite of any friction in the system.

To prevent the web 15 from advancing further than the positive drive from the rack 45 due to inertia in the system, a brake 56 is included to stop the drive gear 50 upon reversal of the rack. Any suitable brake may be used for this purpose, and it has been found that an electric brake such as the commercial device sold under the trade name "Magnabrade" by Vickers Electric Division of the Sperry Corporation, is highly efficient for this purpose. This brake comprises two rotating members or surfaces separated by a constant gap having magnetic particles. When the brake stator coil is electrically energized, lines of magnetic force develop which will, by magnetic attraction, stop one rotating member if the other is stopped. In the present invention, the drive shaft 47 is coupled to one brake element and a second shaft 57 is coupled to the other. Drive gear 50 is connected to shaft 57 by gear 58, shaft 59 and gears 60 and 61. Thus, upon reversal of shaft 47, any inertial tendency of gear 50 to continue to rotate is prevented by the operation of

brake 56 whose magnetically coupled surfaces are then trying to rotate in opposite directions.

From the foregoing description, it is apparent that the rack 45, when driven in one direction by its planetary gear system, feeds the paper web 15 to the dies by operation of feed rolls 18 and 19. When the rack is driven in the opposite direction, the feed rolls and the web are stopped. The length of feed in each cycle is directly proportional to the length of travel of rack 45 in one direction. To adjust the length of feed, an arcuate rack 64 is fastened to the outer periphery of ring gear 40 so that the ring gear may be turned by a worm 65. As best shown in FIG. 2, the worm may be operated by a hand wheel 66 affixed to one end of the worm shaft 67. The turning of ring gear 40 by means of the worm 65 changes the initial position of planet gear 39 and thus alters the length of travel of roller 41 which drives the rack 45.

The worm adjustment may be used not only to adjust the feed of the web 15 to a major degree, as changing from 36 inches to 18 inches at the start of an operation, but also to minutely adjust the feed to compensate for small errors during the operation. The latter may be accomplished manually by means of wheel 66 or automatically by suitable control means. A very simple automatic control includes a lever 69 attached to a collar 70 having an integral friction disc 71. The collar 70 and disc 71 are loosely mounted on worm shaft 67 but are frictionally coupled by a friction disc 72 keyed to the worm shaft. Preferably, shaft 67 is split at 73 and the two parts keyed to each other in such manner as to permit the hand wheel and right hand portion of the shaft to be pulled to the right so as to move the disc 72 out of frictional contact with disc 71, thus operatively disconnecting the lever 69 from the shaft while the worm 65 is being adjusted manually.

The free end of lever 69 is disposed between a pair of solenoids 74, 75 and resiliently biased to a central position between the plungers thereof by coil spring 76. The solenoids are connected in parallel across a source of power through a switch 77 arranged to make one, or the other or neither. The switch 77 is actuated by a conventional reflective photocell, or electric eye, circuit generally referenced by block 78, the photocell being designated 79 and positioned above the web 15 between the feed rolls 18 and 19, as shown in FIG. 1.

The paper being fed to the cutter dies normally bears indicia or markings so that if the feed is too great or too small the electric eye circuit 78 will generate out of register signals of different types or polarity. These out of register signals are used to impulse one or the other of solenoids 74, 75 through a mechanical, electrical or electromagnetic tie between the photoelectric circuit and switch 77. When a solenoid is energized, the lever 69 is moved slightly thereby causing the worm 65 to rotate the ring gear 40 in a direction to correct the advance or feed of the web. After each correction, the springs 76 return the lever 69 to its center position between the solenoids. Thus, the corrective adjustments of gear 40 do not accumulate.

If the machine operator notices that the corrections are occurring too frequently, he may pull hand wheel 66 to disengage the lever 69 from worm shaft 67 and manually turn the worm to a new feed setting which will permanently correct the web feed. Releasing the hand wheel will reengage frictional couplings 71, 72 to activate the automatic means for fine adjustments through the electric eye system described. In a preferred embodiment, good results are obtained by design of the planetary gearing system and its adjustment worm to provide a web correction of 0.005" with $\frac{1}{8}$ " stroke of the solenoid plungers.

A practical embodiment of the planetary gear and rack portion of the described feed-up drive is illustrated in FIGS. 5, 6 and 7. This portion of the drive is here shown enclosed in a circular, pan-shaped housing 80 whose open

side is closed by a flat wall 81 of the machine 10. The shaft 36, FIG. 2, for elliptical gear 35 is coupled to the input shaft 36' by coupling 82. The input shaft 36' is journaled in suitable bearings and seals in an opening in casing 80. The crank 37 is constituted by a hub on which the shaft 38 of the planet gear 39 is eccentrically mounted.

The hub 37 is journaled by a bearing 83 in a ring support 84 carried by the ring gear 40 which in turn is journaled in the casing 80 by a bearing 85. The stub shaft 42 carrying roller 41 on an axis in line with the pitch circles of planet gear 39 and ring gear 40 in its extreme positions is supported by a cranklike support arm 86 fastened to planet gear 39. The Scotch yoke 43 is disposed at an angle to the vertical within casing 80, as best shown in FIG. 6, the rack 45 being extended from both sides of the yoke for movement in bearings 87, 88 secured in diametrically opposed openings in the casing 80.

Also within casing 80, and secured to the ring gear 40 through the intermediate ring support 84, is the arcuate worm segment 64 in meshing engagement with the worm 65. The worm shaft 67 is journaled in and projects out of the bottom of the casing by means of suitable bearings and seals 89, 90 for operation by means of the hand wheel 66 or a suitable automatic control system. In this embodiment, the automatic electric eye adjustment, previously described, is not shown. The housing 80 is provided with openings for oil fill, oil drain and venting, these being normally closed by the usual plugs respectively shown at 92, 93 and 94.

The operation of the improved feed-up drive described above should now be apparent with the following additional clarification. Referring to FIGS. 1-3, particularly, the input to the cutter die eccentrics is arranged to vary from approximately 150 r.p.m. for feed of a 36 inch sheet to approximately 240 r.p.m. for an 18 inch sheet. Each rotation, or cycle, of the cutter crank shaft includes about 255° turn while the cutter dies are open for feed of the paper web and about 105° of turn while the dies are closed and the feed is stopped. The timing belt 25, as previously explained, synchronizes the rotation of input gear 28 of the feed-up drive with that of the die eccentric crank shaft.

In the feed-up drive, the operation of elliptical gears 34 and 35 is such as to drive rack 45 to the right in FIG. 3 during the 255° turn of the die crank shaft to feed the web to the dies. During this portion of the cycle, the paper web is accelerated from stop to about 800 feet per minute during the first 40° turn of elliptical gear 34. This speed is maintained substantially constant during turning of the gear from 40° to about 200°, and from 200° to 255° the paper is decelerated from 800 feet per minute to a complete stop. While the elliptical gear 34 completes its turn, i.e., the remaining 105°, the gear 35 turns 180° during reversal of the rack 45, but feed of the paper web remains stopped by reason of operation of the overrunning clutch 48 and brake 56.

Small correction adjustments in the feed length of the web may be made manually by the machine operator or automatically by operation of the electric eye system, as previously explained. Moreover, the rack 64 and worm gear 65 also enable major adjustment of the feed length. For example, in a preferred embodiment, an adjustment of nine revolutions of hand wheel 66 is sufficient to rotate the ring gear 40 through 33° and to change the paper

feed lengths from 18 inches to 36 inches. It is apparent that the described feed-up drive is highly advantageous in that these adjustments to the feed may be made without stopping the machine to change gears or cams.

As previously stated, the planetary system may include a sun gear, either in place of the planet carrying crank 37, or as a main gear in place of the ring gear 40. In the latter event, the adjustment of the sun gear would effect variation of the feed-up drive. Similarly, other adjustment arrangements may be employed, especially for small corrections, but the rack 64 and worm 65 have the advantage of accuracy and the ability for major adjustment of feed length.

Although certain specific embodiments of the invention have been shown and described, it is obvious that many modifications thereof are possible. The invention, therefore, is not to be restricted except insofar as is necessitated by the prior art and by the spirit of the appended claims.

That which is claimed as new is:

1. In combination with a creasing and blank forming press and press operating means for closing and opening the dies of said press, a drive for intermittently feeding a predetermined length of web material, comprising a pair of feed rolls, a drive gear for said rolls, a drive shaft, an overrunning clutch connecting said drive gear and shaft to turn the gear in one direction only, a pinion on said shaft, a rack engaging said pinion for turning said shaft in two directions, a rotatably mounted ring gear, a planetary gear meshing with and revolvable around said ring gear, a crank on said planetary gear and drivingly connected with said rack, and control means engaged with said ring gear for normally retaining said ring gear stationary but enabling angular adjustment thereof to selectively vary the length of web material fed by each stroke of said rack, and including an arcuate rack affixed to said ring gear and a worm in mesh with said arcuate rack, drive means connecting said press operating means and said planetary gear to synchronize the feed of web by said feed rolls with the opening of the press dies, and means for automatically turning said worm to adjust the length of web feed to a predetermined length and including a lever frictionally secured to the worm shaft, a pair of solenoids arranged to move the lever in opposite directions, and photoelectric means disposed near said feed rolls at the entrance of the web to control operation of one or the other of said solenoids in accordance with the over or under length of web being fed to the press.
2. A machine according to claim 1 wherein the plungers of said pair of solenoids are connected to said lever by springs normally biasing the lever to a central position.
3. A machine according to claim 2 wherein said lever is disengageable from the worm shaft by manual means provided for turning said worm and adjusting said arcuate rack.
